UNITED STATES PATENT OFFICE.

CHARLES PALM, OF NEW YORK, N. Y., ASSIGNOR TO HIMSELF AND JULIUS FECHTELER, OF SAME PLACE.

DESIGN FOR THE ORNAMENTATION OF SEWING-MACHINES.

SPECIFICATION forming part of Design No. 12,407, dated August 9, 1881.

Application filed June 30, 1881. Term of patent 7 years.

To all whom it may concern:

Be it known that I, CHARLES PALM, of New York, in the county and State of New York, have invented a new and original Design for the Ornamentation of Sewing-Machines, of which the following is a specification.

This invention relates to a new and original design for the ornamentation of sewing-machines and other articles; and it consists in the novel grouping and configuration of figures hereinafter more fully described.

The accompanying illustrations show, in Figures 1 and 2, opposite views of a sewing-machine plate and arm having thereon my new design. Figs. 3 and 4 are enlarged detail views of the ornamentation at the sides of the cloth-plate; Figs. 5, 6, 7, and 8, enlarged detail views of the ornamentation at the front portion of the cloth-plate. Fig. 9 is an enlarged detail view of the ornamentation at the side of the post of the sewing-machine arm. Fig. 10 is an enlarged detail view of the ornamentation at the side of the sewing-machine arm. Fig. 11 is an enlarged detail view of the ornamentation of the needle-carrying arm. Figs. 12 and 13 represent the ornamentations at the top of the arm.

The figure A is a curled vine having scrolled ends and intermediate scrolls with daisy-like flowers on its stems and with buds and leaves, as shown. The figure A covers the cloth-plate at its sides. The front portion of the cloth-plate is ornamented with the figures B and C, there being two figures B and two figures C, as shown. Each of these is also a curled scroll-like vine, with one daisy and one bud above the flower, similar to those shown in figure A.

The figure D, which ornaments the stem or supporting-post of the needle-arm, is a scroll-like vine, double at its lower part and single

at its upper part, containing a daisy and a bud and leaves, as shown.

The figure E is composed of two small scrolls at opposite ends of the inscription "Domestic," or other inscription, which is placed against 4 the side of the sewing-machine arm.

Figure F, which decorates the needle-arm, is an S-shaped scroll having a daisy-like flower and upwardly-projecting bud and leaves, as shown.

The figures G and H, which ornament the upper part of the sewing-machine arm at the front and back, are small scrolls with leaves and flowers, as shown.

I claim—

1. The design for the ornamentation of sewing-machines consisting of the figure A, substantially as shown.

2. The design for the ornamentation of sewing-machines, consisting of the figure B, substantially as shown.

3. The design for the ornamentation of sewing-machines, consisting of the figures A, B, and C, substantially as shown.

4. The design for the ornamentation of sewing-machines, consisting of the figure D, substantially as shown.

5. The design for the ornamentation of sewing-machines, consisting of the figure F, substantially as shown.

6. The design for the ornamentation of sewing-machines, consisting of the figures D, E, and F, substantially as shown.

7. The design for the ornamentation of sewing-machines, consisting of the figures A, B, C, D, E, F, G, and H, substantially as shown.

CHAS. PALM.
